UNITED STATES PATENT OFFICE.

WILLIAM R. FEARN, OF CAMDEN, NEW JERSEY.

DIRECT-LIFTING HYDROAEROPLANE.

1,256,670.

Specification of Letters Patent. Patented Feb. 19, 1918.

Application filed March 22, 1917. Serial No. 156,590.

To all whom it may concern:

Be it known that I, WILLIAM R. FEARN, a citizen of the United States, residing at Camden, in the county of Camden and State 5 of New Jersey, have invented new and useful Improvements in Direct-Lifting Hydro-aeroplanes, of which the following is a specification.

My invention relates to new and useful 10 improvements in direct lifting hydro-aeroplanes, and has for its object to provide a device of this character with a pair of wings or fins projecting in opposite directions from the body or car, said wings each having 15 two planes or planing surfaces, thereby constructing a flying machine after the manner of a monoplane with approximately the double amount of planing surface.

A further object of the invention is to 20 provide an aeroplane with wings, each wing having two planes lying at an angle to each other, or converging toward their outer edges.

Another object of the invention is to provide a direct-lifting hydro-aeroplane 25 consisting of a body or car carrying an air tight cylinder on each side thereof, said cylinders having arms rotatable thereon which form a part of the framework of the 30 wings and means for raising or lowering said wings.

A further object of the invention is to provide an aeroplane consisting of a body 35 in the form of a housing, car or boat, a keel projecting from the bottom of said body, a runner hinged to the rear end of said keel, gas containing cylinders carried by the sides of said body and diverging rearwardly, wings adapted to rotate about the cylinders 40 comprising arms, a suitable framework and planes, means for raising or lowering said wings, a lifting propeller and a driving propeller.

A still further object of the invention is 45 to provide an aeroplane of the class mentioned having a keel, the same being divided vertically or formed of two hinged members adapted to be raised and lowered or opened and closed.

With these ends in view, this invention 50 consists in the details of construction and combination of elements hereinafter set forth and then specifically designated by the claims.

In order that those skilled in the art to 55 which this invention appertains may under-

stand how to make and use the same, I will describe its construction in detail, referring by numerals to the accompanying drawings forming a part of this specification, in 60 which—

Figure 1, is a side elevation of a direct lifting hydro-aeroplane made in accordance with my improvement.

Fig. 2, is a section at the line 2—2 of 65 Fig. 1.

Fig. 3, is a plan view thereof on a reduced scale; and

Fig. 4, is a fragmentary section similar to Fig. 2, showing a modified form of keel. 70

In carrying out my invention as here embodied 2 represents a body to be used as a car or boat, the sides thereof converging toward the front end as plainly shown in Fig. 3. The walls of the body are provided with the necessary observation slots 3, and along the bottom or underside thereof is arranged a keel 4, the rear end thereof having a rudder or steering plane 5 hinged thereto, said rudder or steering plane having steering 80 chains 6 attached thereto running into the body. On each side of the body is mounted an air tight cylinder 7 each end of said cylinders being conical in shape as at 8. These cylinders are arranged at an angle to 85 each other and converge toward their forward ends, the forward conical portions thereof being in contact with each other and secured together.

At suitable points or positions on said 90 cylinders are rotatably mounted the rings 9 of the swivel arms or spars 10. To these arms are secured the framework or ribs 11, thereby forming the skeleton for the wings 12. The ends of the framework or ribs 11 95 are pivotally attached to the ends of their respective cylinders. Over the framework of each of the wings is stretched the planing surface or material 13 providing upper and lower planes 14 and 15 respectively, said 100 planes being arranged at an angle to each other or converging toward the outer edge of the wings. These wings are adjustable to different positions according to the direction of travel of the machine, said wings being lowered while the aeroplane is rising, and raised when the machine is descending, although it is to be understood that the wings may be lowered when descending so that they will act after the manner of a 110 parachute.

In order that the wings may be adjusted

or raised and lowered I provide a suitable operating mechanism 16 similar to a steering wheel to which are attached suitable cables 16 such as chains, said cables being connected 5 with the rings 9 of the arms 10. By drawing in on certain of said cables and letting out on the other, the wings may be raised or lowered as desired.

The planes 14 and 15 lying at angles to 10 each other or diverging toward the body assist in shedding the winds, thereby greatly adding to the stability of the craft.

At the rear of the device is arranged a 15 driving propeller 18, causing the aeroplane to be driven forward when in the air or upon the water, and a second or lifting propeller 19 is arranged above the body and is adapted to lift the aeroplane from the surface of the water, ground or other resting place.

20. In practice the cylinders 7 are filled with a suitable gas in order that a certain amount of buoyancy will be given the aeroplane which will assist in lifting the same or cause the craft to float upon the surface of a body 25 of water, or in other words a sufficient amount of gas will be carried to greatly relieve the lifting strain upon the lifting propeller.

When everything is in condition for flying 30 the wings 12 are lowered so as to relieve the pressure of air upon the upper planes 14 during the ascent of the machine, the lifting propeller 19 is then started which will cause the aeroplane to be raised from its resting 35 place. After the aeroplane has been raised to the proper altitude, the wings 12 are raised to a horizontal position and the driving propeller 18 started and the lifting propeller 19 stopped. As soon as the driving 40 propeller 18 is started the aeroplane will be forced forward on a horizontal line, and if it is necessary to descend the wings 12 may be raised to the desired height which will cause the aeroplane to gradually drift downward 45 or descend to the desired altitude.

When it is desired to descend and land, the driving propeller 18 is stopped and the lifting propeller 19 is started, the speed of the latter being decreased sufficiently to permit 50 the aeroplane to descend at the proper speed, and the wings 12 at the same time may be raised to relieve the pressure of air upon the lower planes 15.

If for any reason the machinery should 55 get out of working order and the aeroplane begins to descend, the wings 12 may be low-

ered so that they will operate after the manner of a parachute and prevent the craft from swiftly descending.

When the aeroplane is in the air the combined rudder and steering plane 5 is used for guiding the same from side to side, and while the craft is in the water, the same is used as the rudder of the boat.

In Fig. 4 I have shown a slightly modified 60 form of my invention in which the keel 4 is split vertically and longitudinally, or is formed from two similar members 20 hinged or pivoted to the underside of the body as at 21, whereby said members may be moved 70 away from or toward each other, so as to raise and lower or open and close said members. These members are operated in any suitable manner as by cables 22, one of which is attached to each member, and to a 75 suitable sheave 23. These members 20 when lowered or closed as shown in Fig. 4 are used as a stabilizer when flying, and as a keel when resting upon or sailing in a body of water, but when it is desired to alight upon 80 a solid resting place such as the ground the members 20 of said keel are drawn up against the bottom of the body and form a flat resting surface.

Of course I do not wish to be limited to 85 the exact details of construction as herein shown, as these may be varied within the limits of the appended claims without departing from the spirit of my invention.

Having thus fully described my invention, 90 what I claim as new and useful, is—

1. In a device of the character stated a body, gas contained cylinders carried by said body and diverging from their forward toward their rear ends, adjustable wings rotatable about said cylinders, a lifting propeller 95 and a driving propeller.

2. In a device of the character stated a body, gas contained cylinders carried by said body and diverging from their forward 100 toward their rear ends, arms carried by said cylinders and rotatable thereabout, a framework carried by said arms, a pair of planes projecting from the cylinders to the framework and converging toward their outer 105 ends, a keel carried by the bottom of the body, a rudder hinged to said keel, a driving propeller and a lifting propeller.

In testimony whereof, I have hereunto affixed my signature.

WILLIAM R. FEARN.
